UNITED STATES PATENT OFFICE.

EDWARD C. MYERS, OF MILWAUKEE, WISCONSIN, ASSIGNOR TO WEHR COMPANY, OF MILWAUKEE, WISCONSIN.

ADJUSTABLE HOUSING FOR GOVERNORS.

Application filed May 13, 1926. Serial No. 108,784.

This invention pertains to improvements in throttling governors for internal combustion engines.

At the present time conventional types of throttling governors are either driven by the various motor shafts or off the fan belt. Driving the governors directly from the engine requires additional expense of added gearing, shafts, and the like, which are all subject to wear and require continual lubrication. It is therefore a recognized fact that the simplest and least expensive method of driving a governor is from the fan belt. However, this method develops certain objections, due to the fact that it requires proper alining of three pulleys with the fan belt, namely, the drive pulley, fan pulley, and governor pulley. Should any of these be slightly out of alinement, the belt is caused to climb, which results in undue wear upon the same, or jumping of the belt from the pulley. In an endeavor to overcome these objections attempts have been made to incorporate a governor directly in the fan pulley, but these have not been successful, due to the fact that it is impossible to increase the size of the fan pulley sufficiently to permit a practical structure of governor to be housed therein.

It is therefore the primary object of the present invention to overcome the foregoing objections and difficulties by the provision of a simple, compact and efficient throttling governor combined with the fan belt pulley.

A further object resides in the method of attaching the governor whereby the pulley may be adjusted in various directions to insure a tight belt and proper tracking of the same.

A more specific object resides in the adjustable attachment of the throttling governor with the elbow connection between the water jacket of the motor and the radiator, whereby the governor is combined with the fan belt pulley in the confined space between the engine and the radiator.

With the above and other objects in view, which will appear as the description proceeds, the invention resides in the novel construction, combination and arrangement of parts substantially as hereinafter described and more particularly defined by the appended claims, it being understood that such

changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

Figure 1 is a front elevational view illustrating a throttling governor constructed in accordance with the present invention and the method of attaching the same to a portion of the engine.

Figure 2 is a side elevation of the same. Figure 3 is a detailed sectional view taken on the line 3—3 of Figure 1.

In conventional structures of tractors and power units now upon the market, it is highly desirable that the same be as compact as possible. Consequently, the space between the motor and radiator is confined to a minimum, which renders it difficult to position a governor between the fan and motor. To overcome this it is proposed to attach the governor directly to the elbow connection, which, in conventional structures, is provided between the water jacket of a motor and the radiator. For the foregoing purpose the conventional elbow is replaced by the elbow 1 of special construction, which is provided with a pair of oppositely disposed lugs 2 for the reception of bolts 3 that carry a U-shaped bracket 4. Depending from the elbow is a boss 5 receiving the bolt 6, which bolt passes through the horizontal slots 7 provided in the arms of the bracket 4. By this arrangement it will be readily seen that the bracket 4, which is pivotally carried upon the bolts 3, may be pivotally adjusted and securely locked in adjusted position by drawing up on the bolt 6.

Carried by the bracket 4 is a governor housing 8 having a central shaft 9 journalled therein, which shaft serves to carry a conventional structure of governor mechanism 10, the same serving to rock the arm 11, which arm is connected to the throttling valve lever 12 by means of the link 13. The specific structure of governor mechanism and its method of operation is old and forms no particular part of the present invention.

Consequently, it is thought unnecessary to go into a detailed explanation of the same at this time.

Formed integral with the housing 8 are a pair of oppositely disposed bearing blocks 14, which are provided with longitudinal grooves 15 for the reception of the arms of the bracket 4. By this arrangement the housing 8 is confined in the bracket and slidably carried thereby for vertical adjustment.

A set screw 16 threaded through the lower portion of the bracket 4 and provided with a lock nut 17 engages a boss 18 provided on the bottom of the housing 8 and serves to raise or lower the housing to the desired position.

Pinned or otherwise suitably secured to the shaft 9 is a belt pulley 19 provided in its face with a plurality of tapped openings 20 to permit attachment to the fan blades 21. Thus it will be seen that the pulley 19 serves two functions, namely, to carry the fan blades and drive the governor mechanism. In the customary arrangement the belt drive pulley is usually mounted directly upon the crank shaft of the motor and is therefore positioned in alinement with the fan pulley below the same. It will therefore be seen that in order to tighten the belt the housing 8 and pulley 19 must be adjusted upwardly by means of the set screw 16. In its adjusted position the housing 8 is locked in the bracket 4 by means of a transverse bolt 22 passing through the arms and adapted to contract the same sufficiently to cause them to securely engage the bearing blocks 14, there being a certain degree of resiliency in the arms 4.

In some instances it may be desired to provide the elbow 1 with a water circulating impeller. The elbow is therefore provided with a boss 23 adapted to receive an impeller shaft, the boss being normally closed by means of the threaded plug 24 when the impeller is not used.

From the foregoing description, taken in connection with the drawings, it will be seen that a very simple, compact and efficient structure has been provided, which readily combines a governor with the fan pulley, thereby eliminating the difficulties heretofore encountered in other types of governors. It will also be seen that the pulley 19 can be readily adjusted vertically to insure a tight belt, and through the horizontal adjustment of the bracket 4 the pulley may be easily alined with the driving belt to eliminate climbing of the belt upon the pulley and insure proper tracking of the same.

I claim:

1. A throttling governor housing assembly for internal combustion engines comprising, a U-shaped bracket attached to and straddling a portion of the engine for horizontal adjustment, a housing vertically adjustable in said bracket, governor mechanism con-

tained within said housing, and a pulley for driving said governor mechanism.

2. In combination with an internal combustion engine, an elbow connection between the water jacket of the engine and the radiator, a housing, governor mechanism contained within the housing, and means carried by said elbow for carrying said housing and a pulley for driving said governor mechanism. 70

3. In combination with an internal combustion engine, an elbow connection for the water jacket, a U-shaped bracket adjustably carried by and straddling said elbow, a housing adjustably mounted in said bracket, governor mechanism contained in said housing, and a pulley for driving said governor mechanism. 80

4. In combination with an internal combustion engine having an elbow connection for the water jacket, a bracket adjustably carried by said elbow connection, means for locking the bracket in adjusted position, a housing adjustably carried by said bracket, governor mechanism contained within the housing, and a pulley for driving said governor mechanism. 85

5. In combination with an internal combustion engine, an elbow connection for the water jacket of said engine, a U-shaped bracket adjustably carried by said elbow, a housing, bearing blocks carried by the housing for the reception of the arms of said bracket, means for locking the housing in adjusted position on the bracket, governor mechanism contained within said housing, and a pulley for driving said governor mechanism. 95

6. The combination of an internal combustion engine, an elbow connection between the water jacket of the engine and the radiator, a housing, a governor mechanism contained in the housing, a bracket projecting from said elbow for carrying said housing, a pulley for driving said governor mechanism, and means for adjusting said housing vertically and horizontally with relation to said elbow. 105

7. The combination of an internal combustion engine, an elbow connection for the water jacket of said engine, a governor mechanism carried by said elbow, and means for horizontally and vertically adjusting said governor mechanism with relation to said elbow. 115

8. The combination of an internal combustion engine, an elbow connection for the water jacket of said engine, a U-shaped bracket straddling said elbow and having its ends pivotally secured thereto, a governor mechanism slidably supported in said bracket, means for locking said bracket in adjusted position, and means for locking said governor mechanism in adjusted position. 125

9. The combination of an internal combustion engine, an elbow connection for the water jacket of said engine, a U-shaped bracket straddling said elbow and having its ends pivotally secured thereto to permit horizontal adjustment of said bracket, means for locking the bracket in adjusted position, a governor mechanism slidably car-

ried by said bracket for vertical adjustment, and means for locking said governor mechanism in adjusted position. ¹⁰

In testimony that I claim the foregoing I have hereunto set my hand at Milwaukee, in the county of Milwaukee and State of Wisconsin.

EDWARD C. MYERS.
